SKATING SHOE

George H. Gillis, Leominster, Mass.

Application September 14, 1954, Serial No. 32,269

Term of patent 7 years

(Cl. D7—7)

To all whom it may concern:

Be it known that I, George H. Gillis, a citizen of the United States and a resident of Leominster, Massachusetts, have invented a new, original, and ornamental Design for a Skating Shoe, of which the following is a specification, reference being had to the accompanying drawing, forming a part hereof.

The figure is a side elevational view of a skating shoe showing my new design, the opposite side presenting substantially the same appearance as the side shown.

The dominant feature of my design for a skating shoe resides in the contrasting inserts in the sides thereof.

I claim:

The ornamental design for a skating shoe, as shown and described.
